(57) **CLAIM**

The ornamental design for pushbutton for printer with copying and facsimile functions, as shown and described.

DESCRIPTION

FIG. 1 is a perspective view of pushbutton for printer with copying and facsimile functions;

FIG. 2 is a top view thereof; and,

FIG. 3 is a cross-sectional view thereof taken along the line 3—3 of FIG. 2.

The broken line showing of the perimeter of the push button is for illustrative purposes only and forms no part of the claimed design.
